PRODUCTION OF AROMATICS AND DEHYDROGENATED HYDROCARBONS

James A. Anderson, Jr., Baytown, Tex., assignor, by mesne assignments, to Esso Research and Engineering Company, Elizabeth, N. J., a corporation of Delaware

Application December 11, 1953, Serial No. 397,732

6 Claims. (Cl. 260—668)

The present invention is directed to a method for obtaining aromatic hydrocarbons. More particularly, the invention is directed to a method for purifying aromatic hydrocarbon fractions. In its more specific aspects, the invention is directed to a method for purifying aromatic hydrocarbons and forming valuable hydrocarbons, such as styrene and indene and their alkylated homologues, hereinafter referred to as styrenes and indenes.

The present invention may be briefly described as a method for obtaining aromatic hydrocarbons in which a feed aromatic hydrocarbon fraction containing saturated hydrocarbons and alkylated aromatic hydrocarbons and indanes and boiling in the range between 100° and 550° F. is subjected to a temperature between 1100° and 1200° F. in the presence of hydrogen in an amount in the range of 500 to 2000 cubic feet per barrel of feed stock to form a product containing an appreciated amount of aromatic hydrocarbons and dehydrogenated hydrocarbons, such as styrenes and indenes. The product is rapidly cooled or quenched to a temperature not in excess of 200° F. and the quenched product is then distilled under a reduced pressure at a temperature not in excess of 200° F. to remove hydrocarbons boiling above and below the boiling range of the feed. The distilled product may then be inhibited with a suitable oxidation inhibitor to prevent undesirable reactions of the hydrocarbons on storage.

The temperatures to be employed in the practice of the present invention suitably are in the range between 1100° and 1200° F. At a temperature below 1100° F. the aromatic hydrocarbons are not purified and at temperatures above 1200° F. dealkylation reactions become undesirably extensive. A preferred temperature is about 1150° F.

Pressures may suitably range from 0 to 300 pounds per square inch gauge with desirable results obtained at about 150 pounds per square inch gauge.

The heating operation may be conducted for a time in the range from 1 to 50 seconds with quite desirable results being obtained when a temperature of about 1150° F. is used at about 7 seconds.

The reacting surface in the reaction zone may be either a ceramic surface or it may be an alloy of steel such as one of the chrome-nickel types of the 18-8 or 25-20 type. For the lower alloys, such as 18-8 stainless steel, a word of caution is necessary. Such chrome-nickel steels are subject to attack by the high temperature reaction and it may be desirable to so treat the metallic surface to inhibit the attack of the metallic surface by the reducing atmosphere of hydrocarbons and hydrogen in contact therewith. For example, it may be desirable to include as a component of the feed stock a suitable poison for the metallic surface to prevent the catalyzing and forming of coke bodies, which, in turn, favors the destruction of the alloy by carburization including the formation of metallic carbide. Sulfur compounds are suitable for producing this effect.

The feed stock may suitably comprise aromatic hydro-

carbons containing an excess of about 40% by volume of aromatic hydrocarbons. This stock may contain alkylated aromatic hydrocarbons, such as toluene, xylenes, ethyl benzene, propyl benzene, methylethyl benzene, diethyl benzene and the like. The feed stock may also contain the indanes, such as 1,methylindane; 2,methylindane; 4,methylindane; 5,methylindane; 4,5,6-trimethylindane; 1,1-dimethylindane; 1,2-dimethylindane; 1,2,3-trimethylindane and 1,2,3,4,5,6,7,heptamethylindane. The aromatic hydrocarbon fraction may also contain olefins and saturated hydrocarbons, such as paraffins and naphthenes and compounds such as tetralin and its homologues.

The aromatic hydrocarbon feed may suitably boil in the range between about 100° and about 900° F. but preferably may boil in the range between about 100° and 550° F. While any aromatic hydrocarbon feed may be employed, the feed may suitably be a solvent extract of a kerosene fraction, such as a sulfur dioxide extract. The feed stock may also suitably be a heavy cracked naphtha, a gas oil, and the like, fractions thereof, or solvent extracts of such fractions. The feed stock may contain from about 40% to about 80% aromatics and may be obtained from aromatic rich streams derived by solvent extraction of petroleum distillates or from fractions produced in catalytic conversion operations such as catalytic cracking. The aromatic feed may contain appreciable quantities of sulfur particularly when the aromatic fraction is a solvent extract of petroleum fractions such as sulfur dioxide extracts.

The quenching operation to reduce the temperature to a temperature not in excess of 200° F. may be conducted by contacting the product immediately after it leaves the heating zone with a hydrocarbon quenching liquid at a much lower temperature than the product. For example, a light fraction obtained by distilling the heated product may suitably be used as the quenching liquid. It is desirable that the product be quenched to a temperature not in excess of 200° F. within about 30 seconds after the heating operation has been concluded to prevent polymerization of the product.

After the product has been suitably quenched it is then distilled at a reduced pressure at a temperature not in excess of 200° F. to avoid polymerization and to remove hydrocarbons boiling above and below the boiling range of the feed and to recover a product containing appreciated quantities of aromatic hydrocarbons and also containing dehydrogenated hydrocarbons. This product may be suitably inhibited by adding an oxidation inhibitor to the product.

The product may be further purified by subjecting it to a subsequent treatment which may include treatment with sulfuric acid and other reagents to remove the dehydrogenated hydrocarbons and to allow recovery of the purified aromatics. The product may also be subjected to treatment such as a polymerization operation, including distillation and the like, to convert the dehydrogenated hydrocarbons to products of higher boiling point whereby they may be removed from the purified aromatics and recovered for such use.

The present invention will be further illustrated by reference to the drawing in which the single figure represents a flow diagram of a preferred mode.

Referring now to the drawing, numeral 11 designates a charge line through which a feed stock of the type described is introduced into the system from a source, not shown. This feed stock may contain naphthenes or tetralines naturally occurring in the feed stock or naphthenes which may be added to the feed stock. The naphthenes may serve as a source of hydrogen and may replace part of the hydrogen in the operation. In any event, the feed stock as described is introduced by line

11 and has admixed with it hydrogen introduced from a source not shown by line 12 controlled by valve 13. The mixture of aromatic feed and hydrogen is then introduced by line 11 into a hydrocracking zone 14 containing a coil 15 and which is supplied with heat by burners 16. The temperature of the mixture in coil 15 is raised to a temperature within the range between 1100° and 1200° F. and the mixture passed through the zone under the contact conditions mentioned hereinbefore. A product is obtained which discharges from zone 14 by line 17 into a quenching zone 18 where the hydrocarbon product is rapidly cooled or quenched to a temperature not in excess of 200° F. by means of a hydrocarbon fraction introduced into zone 18 by line 19 from a source which will be described further.

The quenched product from zone 18 is then discharged by line 20 into a distillation zone 21 which operates under a reduced pressure and which is provided with a heating means illustrated by a steam coil 22 and which is provided with suitable vapor-liquid internal contacting means, such as bell cap trays, packing equipment and the like which are conventional to the art. Distillation zone 21 includes all auxiliary equipment normally associated with vacuum distillation operations and which will include means for inducing reflux, condensing and cooling means, evacuating means, and the like.

From distillation zone 21 there is recovered as overhead by line 23 gases and light fractions which are the products of cracking the paraffins and/or naphthenes included with the feed introduced by line 11. These products may be discharged from the system by line 23 for use as may be desired after removal of non-condensibles. A portion of these products is desirably employed as quench by introducing a portion of same by line 19 into quenching zone 18. To this end, line 19 is provided with a valve 24 to control the amount of quench introduced into zone 18.

An aromatic fraction of appreciated aromatic content and containing dehydrogenated products, such as styrenes and indenes, and having substantially the same boiling point range as the aromatic feed is recovered by line 25. Heavier ends are discharged from zone 21 by line 26 and these heavier ends may contain tarry residues which may result from polymerization of some of the product. The tarry residue and any heavy carbonaceous fraction produced in zone 14 and in zone 21 will be of a minor nature.

The aromatic fraction in line 25 may be routed to storage or may be further treated as desired. It may be desirable to add to the aromatic fraction in line 25 an oxidation inhibitor. To this end there is connected to line 25 a line 27 controlled by valve 28 which allows the introduction of an oxidation inhibitor into the aromatic fraction to prevent undesirable reactions from taking place on storage prior to further treatment.

It may be seen from the foregoing description taken with the drawing that a number of features are associated with my invention. The reaction taking place in coil 15 is a hydrocracking operation in which substantially little, if any, coke is formed. In short, heavier products are not formed in the hydrocracking operation. The paraffins and naphthenes are removed from the aromatic hydrocarbons by conversion into lighter fractions, such as olefins. The alkylated aromatics and the indenes are not dealkylated but are dehydrogenated to form desirable styrenes and indenes. The tetralines are converted to naphthalene by a dehydrogenation reaction and may serve also as hydrogen donors. Another desirable feature of the present invention is that hydrogen is not consumed or made in the operation to any appreciable extent. Thus the hydrogen may be recycled to the operation, such as from line 23, if desired, after separation of the liquid hydrocarbons therefrom. Still another desirable result obtained in the practice of the present invention is the desulfurization of the aromatic

rich feed stock by the reaction taking place in the reaction zone 14.

The present invention is particularly advantageous in producing from aromatic fractions of low aromatic content purified aromatic hydrocarbons having a purity greatly in excess of 90%.

In order to illustrate the invention further, a fraction boiling up to 445° F. obtained from a sulfur dioxide extract of kerosene was subjected to a temperature in the range from 1100° to 1200° F. in the presence of 1155 standard cubic feet of hydrogen per barrel of feed. This fraction contained aromatics, alkylated aromatics, indenes, paraffins and naphthenes. The feed was charged to a coil at a vapor velocity of about 21 feet per second and for a contact time of 6.73 seconds. The product obtained had a bromine number of 28.5 and contained 95.7% by volume of aromatics, 1% by volume of olefins and 3.3% by volume of saturates. The initial feed contained 74.4% by volume of aromatics.

In another operation a fraction boiling between about 445° F. and 550° F. obtained from the same sulfur dioxide extract of kerosene was passed through a heating coil at a temperature in the range between 1100° and 1150° F. at a hydrogen rate of 1147 standard cubic feet per barrel. The vapor velocity in this instance was 19.6 feed per second and the contact time was 7.12 seconds. The product had a bromine number of 29 and contained 99.6% by volume of aromatics, 0.2% by volume of olefins, and 0.2% by volume of saturates. In this instance, the feed stock had an aromatic content of 90.7% by volume.

In still another run the total liquid sulfur dioxide extract of kerosene boiling in the range from 300° to 550° F. and containing 82.2% by volume of aromatics was heated to a temperature in the range from 1100° to 1150° F. in a coil in the presence of 1116 standard cubic feet of hydrogen per barrel. The vapor velocity per second was 20 feet and the contact time was about 7 seconds. Under these conditions the product obtained had a bromine number of 27 and an aromatics content of 97.1% by volume, olefins 0.6% by volume and saturates 0.3% by volume. In these several operations the bromine number is an indication of the presence of the dehydrogenated hydrocarbons, particularly the styrenes and indenes. It is to be noted that the product in each instance has a low content of olefins.

In other operations, similar fractions were treated at different temperatures. For example, at 1080° F. a fraction having an initial aromatic content of 74.4% was heated under similar conditions and the aromatic content was raised to 78.5% by volume indicating that a temperature below 1100° F. does not give satisfactory results.

A gasoline fraction from a sulfur dioxide extract of a kerosene fraction was subjected to a temperature of 1150° F., a pressure of 150 p. s. i. g. in the presence of 1000 cubic feet of hydrogen at contact times of 3, 6, and 12 seconds to produce products having aromatic contents of 92%, 96%, and 100% aromatics. The feed stock had an aromatic content of 80 to 85% per volume of aromatics. In these runs the sulfur was reduced from 0.95 weight percent in the feed to levels of 0.3, 0.2, and 0.2 weight percent, respectively, for the three products.

It is to be understood that a feature of my invention is the purification of aromatic hydrocarbons in the presence of hydrogen such that the saturated hydrocarbons which are contained in the feed hydrocarbons are largely converted to products of different boiling points such that they may be removed by distillation. A feature of the invention is that this reaction in the presence of hydrogen does not form coke and tarry bodies. In other words, the reaction coil 15 is not plugged after long operating times. To illustrate this feature, the coil, like coil 15, was opened after running at least 42 hours and

it was found that the coil was free of clogging deposits. In numerous other runs of like duration, coking was not experienced.

The nature and objects of the present invention having been completely described and illustrated, what I desire to claim as new and useful and to secure by Letters Patent is:

1. A method for increasing the aromatic content of a feed stock containing aromatic and saturated hydrocarbons boiling in the range of about 100 to 900° F. which comprises the steps of heating said feed stock at a temperature of about 1100 to 1200° F. and a pressure of about 0 to 300 p. s. i. gauge for about 1 to 50 seconds in the presence of hydrogen and in the substantial absence of any catalytic material to form a product containing an appreciated amount of aromatic hydrocarbons, cooling said product to a temperature of not more than about 200° F. within about 30 seconds, distilling said product to remove hydrocarbons boiling above and below the boiling range of said feed stock and recovering a distilled product containing said appreciated amount of aromatic hydrocarbons.

2. A method for increasing the aromatic content of a feed stock containing aromatic and saturated hydrocarbons boiling in the range of about 100 to 900° F. which comprises the steps of heating said feed stock at a temperature of about 1100 to 1200° F. and a pressure of above 0 to 300 p. s. i. gauge for about 1 to 50 seconds in the presence of hydrogen and in the substantial absence of any catalytic material to form a product containing an appreciated amount of aromatic hydrocarbons, cooling said product to a temperature of not more than about 200° F. within about 30 seconds, distilling said product at a temperature of not more than about 200° F. at a reduced pressure to remove hydrocarbons boiling above and below the boiling range of said feed stock and recovering a distilled product containing said appreciated amount of aromatic hydrocarbons.

3. A method for increasing the aromatic content of a feed stock containing aromatic and saturated hydrocarbons boiling in the range of about 100 to 900° F. which comprises the steps of heating said feed stock at a temperature of about 1100 to 1200° F. and a pressure of about 0 to 300 p. s. i. gauge for about 1 to 50 seconds in the presence of hydrogen in an amount in the range of about 500 to 2000 cubic feet per barrel of feed stock and in the substantial absence of any catalytic material to form a product containing an appreciated amount of aromatic hydrocarbons, cooling said product to a temperature of not more than about 200° F. within about 30 seconds, distilling said product at a temperature of not more than about 200° F. at a reduced pressure to remove hydrocarbons boiling above and below the boiling range of said feed stock and recovering a distilled product containing said appreciated amount of aromatic hydrocarbons.

4. A method for increasing the aromatic content of a feedstock containing aromatic and saturated hydrocarbons boiling in the range of about 100 to 550° F. which comprises the steps of heating said feed stock at a temperature of about 1100 to 1200° F. and a pressure of

about 0 to 300 p. s. i. gauge for about 1 to 50 seconds in the presence of hydrogen in an amount in the range of about 500 to 2000 cubic feet per barrel of feed stock and in the substantial absence of any catalytic material to form a product containing an appreciated amount of aromatic hydrocarbons, cooling said product to a temperature of not more than about 200° F. within about 30 seconds, distilling said product at a temperature of not more than about 200° F. at a reduced pressure to remove hydrocarbons boiling above and below the boiling range of said feed stock and recovering a distilled product containing said appreciated amount of aromatic hydrocarbons.

5. A method for increasing the aromatic content of a feed stock containing aromatic and saturated hydrocarbons boiling in the range of about 100 to 550° F. which comprises the steps of heating said feed stock at a temperature of about 1150° F. and a pressure of about 150 p. s. i. gauge for about 1 to 50 seconds in the presence of hydrogen in an amount in the range of about 500 to 2000 cubic feet per barrel of feed stock and in the substantial absence of any catalytic material to form a product containing an appreciated amount of aromatic hydrocarbons, cooling said product to a temperature of not more than about 200° F. within about 30 seconds, distilling said product at a temperature of not more than about 200° F. at a reduced pressure to remove hydrocarbons boiling above and below the boiling range of said feed stock and recovering a distilled product containing said appreciated amount of aromatic hydrocarbons.

6. A method for increasing the aromatic content of a feed stock containing saturated hydrocarbons and at least 40% of aromatic hydrocarbons, said hydrocarbons boiling in the range of about 100 to 550° F., said method comprising the steps of heating said feed stock at a temperature of about 1150° F. and a pressure of about 150 p. s. i. gauge for about 1 to 50 seconds in the presence of hydrogen and in the substantial absence of any catalytic material to form a product containing an appreciated amount of aromatic hydrocarbons, cooling said product to a temperature of not more than about 200° F. within about 30 seconds and distilling said product at a temperature of not more than about 200° F. at a reduced pressure to remove hydrocarbons boiling above and below the boiling range of said feed stock and recovering a distilled product containing said appreciated amount of aromatic hydrocarbons.
